UNITED STATES PATENT OFFICE.

DORA CONWAY, OF TULSA, OKLAHOMA.

CLOTHESPIN BAG.

Application filed March 5, 1925, Serial No. 13,340. Renewed December 29, 1926.

This invention relates to a clothes pin bag including a receptacle and supporting frame and contemplates principally a construction which will enable a removal of the receptacle from the frame to permit the washing of the bag or the substitution of a new part.

Another feature resides in the provision of a cheap and desirable construction of such a nature as to permit convenient adjustment and application of the parts with relation to each other as well as the manipulation of the entire device in use on a line.

Other features will more clearly herein-
15 after appear by reference to the accompany-
ing specification and drawing, wherein like
reference numerals designate corresponding
parts throughout the several views in which,

Fig. 1 is a front elevation,

20 Fig. 2 is a rear elevation showing the sup-
porting arms disconnected and separated,

Fig. 3 is a front elevation of the frame,

Fig. 4 is a side elevation of the upper loop
of the frame, and

25 Fig. 5 is an end view of a slightly modi-
fied form.

Referring now to the details of construction, the body of the receptacle is formed preferably of suitable washable fabric and comprises the sides 1 and 2 stitched together at their ends and bottom. The side 1 is turned inwardly and stitched to form a tube 3 for the passage of the body 6 of the supporting member or frame. Tubular fabric extensions 4 and 5 are secured at the extremities of the tube section 3 to enclose and fasten the bag on the arms 7 and 8 of the frame. This frame or support is in the nature of an integral wire construction and the arms 7 and 8 are formed by bending the body at intermediate points upwardly and inwardly to a point of intersection spaced above the body a sufficient distance to avoid interference with the mouth of the bag.

45 The arm 7 of the wire frame is of greater length than the arm 8 and is looped at 9, the point of intersection. This point of intersection in order to provide for equal balance of the receptacle is equi-distant from the extremities of the body portion 6 of the support. After forming the loop 9 the wire forming the arm 7 extends vertically a suitable distance and is coiled slightly in excess of a complete circle and in a direc-
50 tion opposite to the loop 9, to provide a fastener 10 for engagement with a clothes
55

line of convenient manipulation as shown from Figure 3. Attention is directed to the fact that the adjacent faces of the wire forming the fastening coil 10 are spaced to 60 permit introduction of the clothes line. The extremity of the arm 8 is formed with a hook 11 which engages in the loop 9 thereby forming an easily disconnected fastener.

It will be seen that the arms 7 and 8 project through the tubular extensions 4 and 5 near the point of intersection of the former and these tubes 4 and 5 extend sufficiently beyond this point to permit their folding inward over the loop 9 and hook 11 thereby 65 concealing the latter and retaining same in engaged position. To retain the extremities of the tubular members 4 and 5 over the connection 9—9, snap fasteners 12 are provided and, as shown, the sections of these 70 fasteners are spaced to form a neat appearance of the parts. Obviously suitable fastening may be provided at these points.

The side portion 2 of the body is turned 75 inward to reinforce the upper edge and also 80 to make a finished appearance at this point. By turning in a greater width of material at the upper edge of wall 2 than is turned in at the upper edge of wall 1, the ends of the tube 3 are left free for stitching to the extensions 4 and 5, and the wire has a direct 85 passage which eliminates catching and injury to the material during assembly.

In Fig. 5 a slight modification is shown in that the tubular extensions 4 and 5 are 90 formed integral with the side 1 of the receptacle. This figure also illustrates the continuous nature of the passage for the wire.

In Fig. 1 the present invention is shown 95 ready for use on a clothes line. By a tilting of the bag or a twisting of the line, same can be separated. Should it be desired to remove the bag from the supporting frame, the overlapped extremities of the extensions 4 and 5 are unwrapped and the arms 7 and 100 8 of the support are disengaged at the loop 9. The arms 7 and 8 can then be separated and drawn from the tubular casing heretofore described. The assembly is as easily 105 accomplished.

Obvious numerous changes in the details of construction can be made without departing from the spirit of the invention, the essence of which is set forth in the annexed claims:

110 1. A clothes pin bag including an integral frame comprising a body portion and inter-

secting arms, means for detachably securing said arms together at their point of intersection, one of said arms having an extension above said intersection, and a receptacle carried by said frame.

2. A clothes pin bag including a frame comprising an intermediate body portion and upwardly extending arms, a hook formed at the extremity of one of said arms, a loop for engagement therewith formed in the other arm, and a receptacle removably secured through a portion of its upper extremity to said frame.

3. A device of the class described including in combination a frame comprising an intermediate portion and upwardly extending intersecting arms, means including a hook in one arm and a loop in the other for securing said arms together at their point of intersection, a bag, and means including a bag portion for detachably securing said bag to said frame, whereby said frame serves as a bag support.

4. A device of the class described including in combination a frame comprising an intermediate portion and upwardly extending intersecting arms, means for detachably securing said arms together at their point of intersection, a bag formed with a tubular upper portion for enclosing the intermediate portion and means for securing said bag to said arms.

5. In a device of the class described, a fabric bag including adjacent walls, one of said walls being of greater height than the other and being formed at its upper extremity with a tubular portion, tubular extensions fixed to the extremities of the tubular bag portion, and a frame for supporting said bag extending through the tubular portion of said bag and its extensions and being bent upwardly and inwardly to a point of

intersection and a hook carried by said frame.

6. In a device of the class described, a bag including adjacent walls, one of said walls being turned inward and stitched to form a tubular portion, tubular extensions stitched to the extremities of said tubular portion to form an elongated tube, a supporting frame formed of a single piece of wire extending through said tube, said frame being bent at intermediate points to a point of intersection spaced above the center of said tube, a loop formed at the point of intersection by one of the extremities of said frame, a hook formed by bending the other extremity of said frame adapting to engage said loop, the extremity forming said loop extending vertically above the looped portion and terminating in a rope engaging coil, and fasteners provided at the extremities of said tubular extensions.

7. A device of the class described including a fabric bag formed with a tubular portion at the upper edge of one side, a wire frame extending through said tubular portion and being bent upwardly and inwardly to a point of intersection, means for detachably securing said upper frame portions together at the point of intersection a rope engaging loop arranged in said wire above said securing means, said tubular portion of said bag being extended to enclose the bent portions of said frame and extending beyond the intersection of the latter, and snap fastener sections arranged at points near the extremities of said tube extensions and inward of said point of intersection to permit the wrapping and fastening of same thereabout.

In testimony whereof I affix my signature.

DORA CONWAY.
